G. S. MANNING.

Carriage-Spring.

No. 39,297.

Patented July 21, 1863.

UNITED STATES PATENT OFFICE.

G. S. MANNING, OF SPRINGFIELD, ILLINOIS.

IMPROVEMENT IN WHEEL-VEHICLES.

Specification forming part of Letters Patent No. 39,297, dated July 21, 1863.

To all whom it may concern:

Be it known that I, G. S. MANNING, of Springfield, in the county of Sangamon and State of Illinois, have invented a new and useful Improvement in Wheel-Vehicles; and I do hereby declare that the following is a full, clear, and exact description of the same, reference being had to the accompanying drawings, making a part of this specification, in which—

Figure 1 is a side sectional view of a wagon with my invention applied to it; Fig. 2, a detached portion of my invention; Fig. 3, a section of Fig. 2, taken in the line *x x*.

Similar letters of reference indicate corresponding parts in the several figures.

This invention relates to an improvement in the springs of wheel-vehicles, the mode of applying them, &c., whereby it is believed that several advantages are obtained over the old or ordinary springs, as hereinafter described.

To enable those skilled in the art to fully understand and construct my invention, I will proceed to describe it.

A represents the body of a wagon, and B the front and back axles of the same.

C represents the springs, one part, *a*, of which is around and underneath the axles, and is connected by a link, *b*, to the other part, *c*. (See Figs. 1 and 3.) The upper ends of the part *a* of the springs of the back axle are attached to the bottom of the body A, as shown at *d*, and the two parts *a c* of the back springs pass through staples *e*, attached to a bar, *f*, which is secured to the bottom of the body A some distance in front of the back axle. The upper ends of the parts *c* simply bear against the under side of the parts *a*. By this arrangement a bent form is given to the springs, as shown clearly in Fig. 1. One or more leaves, *g*, may be added to the springs, if necessary or desired. These leaves are

simply passed through the staples *e*, as shown in Fig. 1. The parts *a* of the springs are secured to the axles by means of clips D, which encompass the axles—one at each side of each part *a* of the springs—and pass through plates E, and are secured thereto by nuts *h*. The plates E are secured to the parts *a* by means of countersinks *i*, which form teats *j*, the teats of the parts *a* fitting in the countersinks *i* of the plates E, and teats *k* on the axles B, fitting in countersinks *i* in the parts *a* of the springs. (See Fig. 3.) By this arrangement it will be seen that the springs are not weakened by having holes made through them in attaching them to the axles. The front springs are applied in precisely the same way as the back springs, the only modification being that which is required in order to admit of the front axle turning, as usual, and which consists in having the staples *e* attached to a hound-bar, *l*, the hounds *m* of which are attached to the fifth-wheel F, and the upper ends of the parts *a* to a cross-bar, *n*, of the fifth-wheel. By this arrangement an economical spring is obtained, one that is durable, and which admits of a longitudinal degree of elasticity—that is to say, of a forward and backward play of the wheels and axles—and which consequently obviates in a great degree the jars and concussions to which wheel-vehicles are liable in coming in contact with stones and other obstructions.

Having thus described my invention, what I claim as new, and desire to secure by Letters Patent, is—

The springs C, composed of two principal parts, *a c*, connected together by a link, *b*, and secured to the axles B and to the vehicle, in the manner substantially as herein set forth.

G. S. MANNING.
